COMBINATION CHILD'S BED, WARDROBE, AND
TOY BOX

Joe Ruiz and Doris R. Ruiz, Oakland, Calif.

Application December 27, 1954, Serial No. 33,702

Term of patent 7 years

(Cl. D5—5)

Fig. 1 is a side elevation,

Fig. 2 is a top plan view,

Fig. 3 is a bottom plan view,

Fig. 4 is a front elevation, and

Fig. 5 is a rear elevation of a combination child's bed, wardrobe and toy box, showing our new design.

The opposite side of the combination child's bed, wardrobe and toy box is substantially the same in appearance as the side shown in Figure 1 of the drawing.

We claim:

The ornamental design for a combination child's bed, wardrobe, and toy box, as shown and described.
